UNITED STATES PATENT OFFICE.

FREDERICK V. HADLEY, OF NEEDHAM, STANLEY BARNABY, OF AUBURNDALE, AND JOHN O. CLARKE, OF FOREST HILLS, MASSACHUSETTS.

VAPORIZER.

Application filed May 23, 1921. Serial No. 472,019.

To all whom it may concern:

Be it known that we, FREDERICK V. HADLEY, STANLEY BARNABY, and JOHN O. CLARKE, all citizens of the United States, 5 residents of Needham, county of Norfolk, of Auburndale, county of Middlesex, and of Forest Hills, county of Suffolk, State of Massachusetts, respectively, have invented an Improvement in Vaporizers, of which 10 the following description, in connection with the accompanying drawing, is a specification, like characters on the drawing representing like parts.

This invention relates to improvements in 15 vaporizing apparatus and particularly to improvements in that type of apparatus in which the liquid is delivered into the path of a gaseous fluid under pressure, such as steam or air, by means of which it is 20 atomized and mixed with the gaseous fluid under pressure.

In usual types of vaporizers or atomizers 25 of this character the action of the gaseous fluid under pressure serves to break up the liquid into relatively small globules which are carried along with the gaseous fluid under pressure, but are not so finely broken up and intermingled therewith as to produce approximate or complete vaporization.

30 The object of the present invention is to provide means for more thoroughly atomizing the liquid and intermingling the same with the gaseous fluid under pressure to produce a homogeneous vapor which may be either wholly invisible or in the form of a fog which after escaping from the vaporizer will soon disappear without precipitation.

The particular embodiment of the invention 40 is disclosed herein as applied to a burner for oils and its object is to provide a device for so thoroughly atomizing the oil and mixing it with a gaseous fluid under pressure, such as steam or air, as to produce a homogeneous mixture which will readily combine with the oxygen of the air to produce complete combustion.

A further object of the invention is to 45 provide a mixing device which may be applied to a usual form of burner head and which will produce thorough atomization or vaporization of the fuel and a homogeneous

mixture thereof with the gaseous fluid under pressure.

A further object of the invention is to 55 provide a novel type of head comprising a settling chamber for the oil from which sediment may be readily removed.

A further object of the invention is to 60 provide a novel type of head of the character described in which a regulated amount of the gaseous fluid under pressure may be introduced into the liquid to increase the pressure and velocity with which the vapour is delivered from said head.

65 Other objects and features of the invention will more fully appear from the following description and the annexed drawings and will be pointed out in the accompanying claims.

70 A preferred embodiment of the invention is illustrated herein as applied to an oil burner head, in which,

75 Fig. 1 is a vertical longitudinal sectional view of an oil burner head, the conduits leading therefrom to a mixing chamber from which the atomized or vaporized fuel is delivered through a suitable nozzle;

80 Fig. 2 is a vertical transverse sectional view on line 2—2, Fig. 1; and,

85 Fig. 3 is an enlarged sectional view on line 3—3, Fig. 1, viewed from the left toward the right.

90 As illustrated in the drawing the head comprises a casing 1, preferably of cast metal such as brass, having a compartment 2 to receive a gaseous fluid under pressure which may be introduced into it through an inlet pipe 3 having screw threaded connection with a boss 4 on the casing. The 95 casing desirably also is provided with a boss 5 diametrically opposite to the boss 4 into which is screwed a conduit 6 through which the gaseous fluid under pressure flows from the chamber 2.

95 The casing desirably is provided with an upwardly extending boss 7 which receives a liquid in a pipe 8. A central tubular conduit 9, formed within and integral with the casing, provides an extension of the inlet pipe 8 and extends nearly to the bottom of a downwardly projecting well 10 which constitutes a settling tank for the liquid. A pipe 11, extending downwardly from the

lower end of the well 10 and provided with a valve 12, provides means for drawing off sediment and residue which accumulate in the bottom of the settling tank.

5 The liquid is delivered from the settling tank through a port 13 which communicates with a conduit 14 which preferably extends axially of and concentric with the conduit 6. It is sometimes desirable, as for example, when cold oil is to be vaporized to provide means for introducing fluid under pressure directly into the liquid which is delivered from the head and this is accomplished by providing an aperture in the wall 15 of the port 13 with a suitable valve for controlling the flow of gaseous fluid under pressure into said port. Furthermore, the gaseous fluid under pressure may be introduced through this aperture for the purpose of blowing out the settling chamber and also for the purpose of cleaning the conduit 14 and the ports through which the liquid is delivered therefrom.

25 In the construction illustrated particularly in Fig. 2 the wall of the port 13 is provided with an aperture 15, the effective area of which is regulated by a needle valve 16 which is adjustably mounted in a boss 17 extending outwardly from the casing. A suitable packing 18 and a cap 19 provides a gland which will prevent the escape of the fluid under pressure.

30 The stem of the valve 15 may be provided with an angular end portion 20 to receive a wrench or hand wheel by means of which the valve may be easily adjusted.

35 A suitable nozzle may be connected directly to the ends of the conduits 6 and 14. In usual types of vaporizers nozzles have 40 been connected to the ends of conduits corresponding in function to the conduits 6 and 14. The present invention, however, comprises the production of a novel type of distributor for the liquid and the gaseous fluid under pressure which is designed to produce 45 a more effective atomization and mixing of the atomized liquid and the gaseous fluid, and further comprises a mixing chamber or a plurality of mixing chambers so constructed 50 and acting as to cause a minute atomization or vaporization of the liquid and a thorough and homogeneous intermingling thereof with the gaseous fluid under pressure and finally delivering the mixture either directly 55 or through a suitable nozzle.

60 As before stated, one of the objects of the invention is to provide means for more effectively atomizing and commingling the liquid with the gaseous fluid under pressure as it emerges from the conduits which lead from the head. In the present construction a special type of distributor is provided which comprises a cylindrical block or plug 65 21 of very slightly less diameter than the interior diameter of the gaseous fluid conduit

6 leaving an annular recess 22 between its periphery and the interior wall of the conduit 6. The distributor 21 is also provided upon its periphery with a series of longitudinally extending channels or jet-producing 70 apertures 23 for the gaseous fluid under pressure.

75 The distributor 21 is provided with a central cylindrical recess 24, the wall of the front end of which is provided with a screw threaded section 25 adapted to engage complementary screw threads upon the end of the oil conduit 14. A series of preferably radial ports 26 lead from this recess into the path of the peripheral jet apertures. Preferably the inner walls of the jet apertures beyond the ports 26 are cut more deeply to provide channels 27 to accommodate the liquid-carrying gaseous jets which issue from the end of the conduit 6. The nozzle thus constructed alone will provide an efficient atomizer, but will not so thoroughly atomize and vaporize the liquid as to produce a strictly homogeneous mixture. Means, therefore, have been provided for more completely breaking up the globules of liquid and mixing them more thoroughly with the gaseous fluid under pressure.

85 This is accomplished in the present invention by providing one or more mixing chambers having abutments or baffles against which the liquid-carrying gaseous jets impinge thus serving to break up the globules of liquid more finely and by causing an eddying or whirling of the gaseous jet within the mixing chamber to more thoroughly commingle the atomized liquid with the gaseous fluid. In the preferred construction a casing 28, which is connected to the end of the conduit 6 by a screw threaded union 29, is provided with one or more mixing chambers having abutments or baffles of the character described. As illustrated herein the casing 28 is provided with a primary mixing chamber 30 which is considerably larger in diameter than that of the conduit 6. Intermediate of its ends it is provided with an abutment 31 which preferably is made integral with the casing and connected thereto by two or more integral webs 32, thus leaving a peripheral outlet 33 from the mixing chamber. The abutment 30 desirably is provided with a conical socket 34 which receives the end of an extension 35 of the distributor 21, the distributor thus being supported in axial relation to the conduit 6 so that the space between the periphery of the distributor and the inner wall of the conduit 6 will provide an annular passage through which a cylindrical envelope of gaseous fluid under pressure will be projected into the mixing chamber which will enclose the liquid-carrying gaseous jets.

90 100 105 110 115 120 125 130 The abutment 31 desirably is provided with an annular concave face 36. The jets

of liquid-carrying gaseous fluid preferably impinge upon the central or outer portion of this channel and the directions of the jets are reversed thereby in such a manner 5 as to cause a rapid eddying in the mixing chamber. Any globules of liquid which are projected against the abutment will be broken up and the cyclonic eddying produced by the rapid reversal of the current 10 also serves to break up the globules of liquid and to cause a thorough intermingling of the same with the gaseous fluid. The mixture thus produced issues through the channel 33 into an extension 37 of the mixing 15 chamber. The walls 38 of this extension converge into a relatively small outlet 39 having outwardly tapering walls 40 leading to a secondary mixing chamber 41. The passage from the extension 37 of the 20 primary mixing chamber to the secondary mixing chamber 41 is so constructed as greatly to increase the velocity of the mixture, the walls 40 being formed to produce an action somewhat similar to that of a 25 Venturi tube. The mixture issuing from this passage at a high velocity impinges upon an abutment 43 which serves further to break up any globules of liquid and to thoroughly and completely commingle the 30 same with the gaseous fluid.

The abutment 43 desirably is made integral with the casing 28 and is connected thereto by narrow webs 44. The mixture issues from the chamber 41 through passages 45 into an extension 46 of the secondary mixing chamber from which it may be led through a suitable tube 47 to a nozzle 48 of any usual type provided with suitable discharge ports 49.

40 In the operation of the device, therefore, the liquid is first introduced through the inlet pipe 8 into the setting tank 10 from which it is conducted through the central conduit 14 and the chamber 24 of the distributor 21 to the ports 26. The steam or air under pressure is introduced through the inlet pipe 3 and passes through the chamber 2 into the conduit 6 which surrounds the liquid conduit 14. A portion 45 of the gaseous fluid then passes through the channels or jet-producing apertures 23 and impinges upon the liquid issuing from the ports 26. Another portion of the gaseous fluid under pressure passes through the annular recess between the periphery of the distributor and the inner wall of the conduit 26, thus providing a substantially cylindrical or conoidal envelope which encloses the liquid-carrying jets which emerge 50 from the deeper channel 23 of the distributor. The liquid-carrying gaseous jet impinges upon the concave annular wall 31 of the abutment 31, which, as before described, causes a cyclonic eddying mixture, 55 while the outer envelope desirably strikes upon the knife-like edge of the abutment at the periphery of the concave channel 36. Thus a portion of said envelope is directed toward the center of the mixing chamber, while a portion thereof tends to pass directly along to the channel 33. This action causes the liquid to be broken up finely and thoroughly intermingled with the gaseous fluid under pressure and then forced 60 through the channel 33 into the extension 37 of the mixing chamber which it enters at a reduced pressure. The mixture then flows through the passage leading to the secondary chamber which, by reason of its construction, causes a considerable increase in 65 velocity of the mixture. After entering the secondary chamber 41 the mixture is projected against the abutment 43 which again causes the mixture to eddy and whirl so that by the time it passes through the channel 45 into the extension 46 of the secondary chamber it is most thoroughly atomized or vaporized and issues from the ports 49 of the nozzle 48 in the form of a 70 fog or an invisible vapor dependent upon the pressure at which the gaseous fluid is introduced and the amount of liquid which is delivered to it. As before stated, a predetermined amount of the gaseous fluid under pressure may also be introduced into 75 the liquid by proper manipulation of the needle valve 16.

Any sediment which may accumulate during the continued use of the vaporizer may be drawn off by shutting off the supply of liquid and opening the valve 12 in 80 the delivery pipe 11. By then opening the valve 16 the sediment may be blown out and the settling chamber thoroughly cleaned.

85 It will be understood that the particular embodiment of the invention disclosed herein is illustrative and not restrictive and that various changes in form, construction and arrangement of parts may be made within the spirit and scope of the following claims. It will also be understood that while the invention is particularly adapted 90 for vaporizing refined or crude fuel oils it may be employed for the purpose of vaporizing other liquids within the spirit and scope of the following claims.

95 Having thus described our invention, what we claim as new, and desire to secure by Letters Patent, is:

1. A vaporizer comprising a casing having a mixing chamber therein, means for introducing an annular series of jets of gaseous fluid under pressure into said chamber, means for delivering liquid in the paths of the respective jets, an abutment having an annular concave deflecting surface in the paths of said liquid-carrying jets acting to cause an eddying thereof in said mixing chamber whereby the liquid will be thoroughly atomized and mixed with said gaseous fluid.

ous fluid and peripheral outlets in the end wall of said chamber for delivering the mixture.

2. A vaporizer comprising a casing having a mixing chamber therein, means for introducing an annular series of jets of gaseous fluid under pressure into said chamber, means for delivering liquid radially into the paths of said jets, an abutment having a 10 concave annular surface in the path of said liquid-carrying gaseous jets acting to reverse the direction of said jets and to cause an eddying thereof in said mixing chamber whereby the liquid will be thoroughly atomized and mixed with said gaseous fluid and means for delivering the mixture.

3. A vaporizer comprising a casing having a mixing chamber therein, means for introducing into said chamber a cylindrical 20 annular series of jets of gaseous fluid under pressure, means for producing an envelope of gaseous fluid under pressure surrounding said jets and means for delivering liquid radially outwardly to said jets.

25 4. A vaporizer comprising a casing having a mixing chamber therein, means for introducing into said chamber an annular series of jets of gaseous fluid under pressure, means for producing an envelope of gaseous 30 fluid under pressure surrounding said jets, means for delivering liquid radially outwardly to said jets, an abutment having an annular concave surface in the paths of said jets acting to reverse the direction of said liquid-carrying jets and to cause an eddying 35 thereof in said mixing chamber and means for delivering the mixture from said mixing chamber.

40 5. A vaporizer comprising a casing having a mixing chamber therein, means for introducing into said chamber an annular series of jets of gaseous fluid under pressure, means for producing an envelope of gaseous 45 fluid under pressure surrounding said jets, means for delivering liquid radially outwardly to said jets, an abutment having an annular concave surface in the paths of said jets acting to reverse the direction of said liquid-carrying jets and to cause an eddying 50 thereof in said mixing chamber, and a series of peripheral ports surrounding said abutment for delivering the mixture from said mixing chamber.

55 6. A vaporizer comprising a casing having a mixing chamber therein, means for introducing an annular series of jets of gaseous fluid under pressure into said chamber, means for delivering liquid radially outwardly into the paths of said jets, an abutment having an annular concave deflecting 60 surface in the path of said liquid-carrying gaseous jets and means for increasing the velocity of the mixture delivered from said mixing chamber.

65 7. A vaporizer comprising a casing hav-

ing a mixing chamber therein, means for introducing an annular series of jets of gaseous fluid under pressure into said chamber, means for delivering liquid radially outwardly into the paths of said jets, an abutment having an annular concave deflecting surface in the path of said liquid-carrying gaseous jets and means for increasing the velocity of the mixture delivered from said mixing chamber comprising a relatively 70 constricted port having an outwardly diverging conoidal wall.

8. A vaporizer comprising a casing having a primary and a secondary mixing chamber therein, means for introducing an annular series of jets of gaseous fluid under pressure into said primary chamber, means for delivering liquid radially outwardly into the paths of said jets, an abutment having an annular concave deflecting surface in the paths of said liquid-carrying gaseous jets acting to cause an eddying thereof in said primary mixing chamber, means for conducting the mixture from said primary into 80 said secondary chamber, an abutment in said secondary chamber against which said mixture is projected and thereby caused to eddy and means for delivering the mixture from said secondary chamber.

9. A vaporizer comprising a casing having a primary and a secondary mixing chamber therein, means for introducing an annular series of jets of gaseous fluid under pressure into said primary chamber, means for delivering liquid radially outwardly into the paths of said jets, an abutment having an annular concave deflecting surface in the paths of said liquid-carrying gaseous jets acting to cause an eddying thereof in said primary mixing chamber, a restricted conduit having an outwardly diverging conoidal wall leading to said secondary chamber acting to increase the velocity of said mixture, an abutment in said secondary chamber in the path of said mixture acting to cause the same to eddy in said secondary chamber and means for delivering the mixture around the periphery of said abutment.

10. A vaporizer comprising a head having a chamber for a gaseous fluid under pressure and a liquid-containing chamber providing a settling chamber, an inlet pipe for the liquid extending well into said settling chamber, a conduit leading from said gaseous fluid chamber and a liquid delivery conduit located concentrically thereof leading from said liquid-containing chamber and means operable to draw off sediment from said liquid-containing chamber.

11. A vaporizer comprising a head having a chamber for a gaseous fluid under pressure and a liquid-containing chamber therebeneath, a conduit leading from said gaseous fluid chamber and a liquid delivery conduit located concentrically thereof leading from 120 125 130

the liquid-containing chamber, a port leading from said gaseous fluid conduit into said liquid delivery conduit for introducing gaseous fluid under pressure into said liquid conduit.

12. A vaporizer comprising a head having a chamber for a gaseous fluid under pressure and a liquid-containing chamber therebelow, a conduit leading from said gaseous fluid chamber and a liquid delivery conduit located concentrically thereof leading from the liquid-containing chamber, a port leading from said gaseous fluid conduit into said liquid delivery conduit for introducing gaseous fluid under pressure into said liquid conduit and a needle valve in said port operable to control or shut off the amount of gaseous fluid delivered into the liquid delivery conduit.

13. A vaporizer comprising a head having a chamber for a gaseous fluid under pressure and a liquid-containing chamber, a conduit leading from said gaseous fluid chamber and a conduit located concentrically thereof leading from said liquid-containing chamber, a distributor secured to said liquid conduit having radially extending ports and loosely fitting within the conduit for said gaseous fluid under pressure and provided

with longitudinally extending grooves providing jet apertures in co-operative relation to said ports whereby the discharge of said fluid under pressure through said jet apertures will atomize the liquid and the space between said distributor and the wall of the conduit will produce an enclosing envelope of said gaseous fluid.

14. A vaporizer comprising a head having a chamber for a gaseous fluid under pressure and a liquid-containing chamber, a conduit leading from said gaseous fluid chamber and a conduit located concentrically thereof leading from said liquid-containing chamber, a distributor secured to said liquid conduit having radially extending ports and provided with peripheral jet-producing recesses co-operating with said ports, a casing secured to said gaseous fluid conduit provided with a mixing chamber and an abutment in said mixing chamber located in the paths of the liquid carrying gaseous jets acting to reverse the direction of said jets and to cause eddying of the mixture in said chamber.

In testimony whereof, we have signed our names to this specification.

FREDERICK V. HADLEY.

STANLEY BARNABY.

JOHN O. CLARKE.

Certificate of Correction.

It is hereby certified that in Letters Patent No. 1,462,504, granted July 24, 1923, upon the application of Frederick V. Hadley, of Needham, Stanley Barnaby, of Auburndale, and John O. Clarke, of Forest Hills, Massachusetts, for an improvement in "Vaporizers," errors appear in the printed specification requiring correction as follows: Page 4, line 19, claim 3, strike out the words "a cylindrical" and insert the word *an*, and line 21, strike out the word "an" and insert the words *a cylindrical*; and that the said Letters Patent should be read with these corrections therein that the same may conform to the record of the case in the Patent Office.

Signed and sealed this 9th day of October, A. D., 1923.

[**SEAL.**]

WM. A. KINNAN,
Acting Commissioner of Patents.
